UNITED STATES PATENT OFFICE.

FREDRICK DANIEL MELVILL, OF KLERKSDORP, TRANSVAAL.

DOOR-STOP.

No. 911,423.

Specification of Letters Patent.

Patented Feb. 2, 1909.

Application filed May 27, 1908. Serial No. 435,237.

To all whom it may concern:

Be it known that I, FREDRICK DANIEL MELVILL, bookkeeper, a subject of the King of Great Britain, residing at Church street, 5 Klerksdorp, Colony of the Transvaal, have invented new and useful Improvements in Door-Stops, of which the following is a specification.

This invention relates to stop devices 10 which are carried by a door and are designed to engage the floor for the purpose of retaining the door in position when open; such devices being frequently employed in conjunction with spring door closing means.

15 The purpose of the present invention is to provide such a stop which is cheap and simple to manufacture and fit up, and which is operated manually and preferably by means of the usual door handles or equivalent devices so as to be operated with equal facility 20 from either side of the door; being applicable to either right or left hand doors and readily adaptable to doors of various dimensions. The stop proper is such as to operate automatically 25 by its own weight and is usually arranged to engage in one direction only.

The invention is illustrated in the accompanying drawings, Figure I being a view (to a smaller scale than the rest of the figures) of 30 the device fitted up for use, Fig. II an elevation of the crank and part of the connecting rod, Fig. III a vertical section and Fig. IV a plan of the stop proper, and Fig. V showing a locking attachment; all these parts being 35 more particularly described hereafter.

Numerai 1 indicates a sheet metal frame or bracket adapted to be secured to the door 2 on the inner side, that is the side towards which the door opens, and near to the lower 40 edge thereof. Pivoted thereon by a pin 3 is the cam or arm 4 having a tread 5 of rubber or other suitable material for engaging the floor; the point of engagement being between the pivot 3 and the door so that in 45 opening the door the cam trails freely over the floor, but operates as a brake upon the movement being reversed. The cam is constructed of a single piece of sheet metal bent to form the two side cheeks 6 and connected 50 at one end by the integral piece 7 and clasped at the other end by a pin 8. An arcuate strip 9 is turned at one end around said pin 8

and is hooked at the other end under the piece 7; said strip 9 serving as a backing for the tread 5, which is clamped between the 55 cheeks 6 and further secured if desirable by one or more pins 10. The stop normally rests upon the floor, and it is raised therefrom by movement of the door handles or equivalent devices. To this end there is provided a crank 11, which, as shown, is simply a plate pierced with a square central hole 12 so that it may be slipped onto the spindle carrying the handle knobs to rotate therewith, being retained in position by the handle 60 13.

The connecting rod for coupling the crank 11 to the cam 4 comprises a metal strip 14 permanently pivoted to the crank and forming one terminal, a second metallic terminal 70 15 pivoted to the cam, said terminals being pierced with screw holes 16, and a wooden intermediate part 17 which may be readily cut to the necessary length and to which the terminals are screwed. The connecting rod 75 is held in place by means of guides 18.

In some cases a tubular or telescopic connecting rod may be employed, having means for clamping the two parts to form a rigid rod of the required length. 80

For holding the stop out of action there may be pivoted to the connecting rod a toothed cam 19 capable of being turned to engage the door and thereby frictionally holding the connecting rod in its elevated 85 position.

In a modified form of the invention more suitable for applying to doors before being hung, the stop and crank are fitted within recesses formed in the door and the connecting rod is carried down a passage formed in the door stile. 90

What I claim as my invention, and desire to secure by Letters Patent, is:—

1. In combination with a door, a gravity 95 acting stop, means for operating the stop, a connecting rod joining said means to the stop and a locking device associated with the connecting rod and adapted to engage the door frictionally.

2. In combination with a door stop and actuating means therefor, a connecting rod comprising terminal pieces permanently joined respectively to said stop and to said 100

actuating means, and a wooden intermediate portion to which the terminal pieces are adapted to be secured.

3. In combination with a door, of a stop actuating device therefor, a stop operatively connected with said device and comprising a pivotally mounted U-shaped cam member, a flat backing strip removably secured within said member, and a segmental tread mem-

ber of yielding material disposed against said 10 backing strip and secured to said cam member.

In testimony whereof I affix my signature in the presence of two witnesses.

FREDRICK DANIEL MELVILL.
